UNITED STATES PATENT OFFICE.

THOMAS E. MISEE AND EMMETT L. TAYLOR, OF BARLING, ARKANSAS.

RAIL-JOINT.

1,130,921.

Specification of Letters Patent. Patented Mar. 9, 1915.

Application filed May 10, 1913. Serial No. 766,860.

To all whom it may concern:

Be it known that we, THOMAS E. MISEE and EMMETT L. TAYLOR, citizens of the United States, residing at Barling, in the county of Sebastian, State of Arkansas, have invented certain new and useful Improvements in Rail-Joints; and we do hereby declare the following to be a full, clear, and exact description of the invention, such as will enable others skilled in the art to which it appertains to make and use the same.

This invention relates to new and useful improvements in rail joints.

The primary object of the invention is to provide an improved form of joint which forms a continuous rail surface thereby obviating the disadvantages of the jolting and wear by the conventional form of rail joints.

A further object resides in the provision of a rail joint of the class described which is so constructed as to obviate the necessity of using auxiliary fastening means such as fish plates and bolts.

The invention further contemplates the provision of a rail joint which shall be of such simple structure as to admit of ready and economical manufacture and which shall be easily applied.

With these and other objects in view, the invention resides in the novel combination, formation and arrangements of parts to be more fully hereinafter described and illustrated in the accompanying drawings and particularly pointed out in the claim hereto appended.

Reference is had to the accompanying drawings wherein similar characters of reference designate corresponding parts throughout the several views, and in which;

Figure 1 is a side elevational view of the improved rail joint, Fig. 2 is a top plan view of what is shown in Fig. 1, Fig. 3 is a top plan view of one of the rail sections, Fig. 4 is a perspective view of one of the rail sections.

Referring more particularly to the drawings, A and B designate the abutting ends of two adjacent sections of railway rails. In order to permit the cutting of the sections to form the novel joint, the webs of these rails adjacent their abutting ends are thickened so as to present in conjunction with the other parts of the rail, a substantially rectangular cross-section. The joint is formed by cutting each of the rails in a similar manner and interlocking the said cut portions as will be

hereinafter disclosed. As the cuts formed in each of the rail joints are similar, it will only be necessary to describe one of the rail portions and the numerals which designate the parts of one rail portion will also be used to designate the respective parts of the other rail section.

Each rail portion is provided with a reduced extension 5, the top and bottom walls 65 and one side wall of which are in alinement with the corresponding walls of the rail portion. The free outer portion of this extension is cut from the bottom face of the extension upwardly at an obtuse angle to the 70 base as at 6 then downwardly at an acute angle thereto as at 7, then upwardly at an obtuse angle as at 8 and forwardly horizontal to the end of the extension as at 9. The cut away end of the extension is further 75 provided with a laterally disposed head 10 which extends to the other side of the rail and which has its forward face beveled as at 11. Rearwardly of the forward extension 5, the top portion of the rail is provided with 80 a recess 12 for seating the head 10 of the other rail section and adjacent this recess there is provided a suitable portion so positioned and formed that its faces 13, 14 and 15 oppose the cut away portions 6, 7 and 8 85 of the extension 5.

From the foregoing it will be observed that a joint is provided which will permit no lateral or upward movement of one rail with relation to the other rail. It will be further observed that it requires practically no time to assemble the cut ends of the rails to form the joint. The beveled faces 11 of the extensions 5 form in conjunction with the adjacent portion of the rail sections a continuous rail surface.

From the foregoing it will be observed that a very simple form of joint has been provided which requires the use of no auxiliary fastening means such as bolts and 100 plates.

What is claimed is:—

A rail joint comprising abutting rails, each rail being longitudinally halved for a distance adjacent its end, the end having thereon a lateral extension the width of the rail tread and being cutaway below said lateral extension to provide steps having inclined faces, and each rail being further provided at the other end of the longitudinally halved portion with a socket extending across the entire tread and being further provided with

2
a step portion at said socket and having inclined surfaces, the lateral extension of each rail fitting within the socket on the other rail, the first named inclined step portion of each rail fitting upon the second named inclined step portion of the other rail and each longitudinal halved portion co-acting with the other.

In testimony whereof, we affix our signatures, in the presence of two witnesses.

THOMAS E. MISEE.
EMMETT L. TAYLOR.
